UNITED STATES PATENT OFFICE.

EMIL H. MEYER, OF SARATOGA, TEXAS.

WIRE-WINDING MACHINE.

Application filed December 22, 1923. Serial No. 682,139.

To all whom it may concern:

Be it known that I, EMIL H. MEYER, a citizen of the United States, residing at Saratoga, in the county of Hardin and State 5 of Texas, have invented certain new and useful Improvements in a Wire-Winding Machine, of which the following is a specification.

This invention relates to new and useful 10 improvements in a wire winding machine.

One object of the invention is to provide a wire winding machine specially designed for the purpose of winding wire on a frame or perforated pipe in the process of manufacturing well screens. 15

Another object of the invention is to provide a machine of the character described whereby the screen wire may be wound on the perforated pipe, or screen frame, in the 20 form of a helix, with its turns spaced a uniform distance apart.

A further feature of the invention resides in the provision of a wire winding machine whereby spacing lugs, of uniform height 25 may be thrown out from the wire as it passes through the machine, and said lugs, being formed of uniform height, need not be cut down to produce evenness in height, and their galvanized coating thus need not be destroyed. 30

A still further feature consists in an improved feeding mechanism whereby a uniform winding of the screen wire is secured.

With the above and other objects in view, 35 the invention has particular relation to certain novel features of construction, operation and arrangement of parts, an example of which is given in this specification and illustrated in the accompanying drawings, 40 wherein:—

Figure 1 shows an end view of the device, partly in section.

Figure 2 shows a side elevation thereof.

Figure 3 shows a plan view.

Figure 4 shows an enlarged vertical sectional view of the wire forming rollers.

Figure 5 shows an enlarged plan view of a section of the screen wire, with the spacing lugs formed thereon; and,

Figure 6 shows a cross section through adjacent turns of the screen wire as wound on the pipe.

Referring now more particularly to the drawings, wherein like numerals of reference designate similar parts in each of the figures, the numeral 1 designates the body

of the lathe. The numeral 2 designates the lathe carriage which runs upon the tracks 3, 3 forming part of the lathe body. The perforated pipe 4, forming the screen frame, 60 is mounted in the lathe, and is rotated from the lathe chuck (not shown) in the well known manner. The carriage is driven along, as winding progresses, by means of the rotary screw shaft 5 which is rotated by 65 the lathe mechanism and which is threaded through the split, tapped bearing 6 carried by the carriage. The pipe 4 is supported on the rollers 7, 7. These rollers are mounted on the bearing rods 8, 8, whose respective ends are anchored to the upper ends of the respective pairs of toggle links 9, 9. The lower ends of these links of the 70 respective pairs, have bearings on a common bearing rod 10, carried by the lathe carriage. 75 The rollers 7, 7, may be adjusted, and the pipe 4 thus elevated or lowered through the adjusting screws 11, 11 which are attached at their upper ends to sleeves 12, 12 on the rods 8, 8, and have screw connections with 80 tapped bearings 13, 13 carried by opposite sides of the lathe carriage. As the carriage moves along, the pipe 4 is rotated and the screen wire 14 is wound, in a helix, on said pipe. The wire passes through between the 85 guide rollers 15, 15 which are mounted in the frame 16. These rollers are spaced apart to allow space for the wire and they will usually be tapered upwardly since the wire, in cross section is usually keystone in 90 shape. The wire is held between the feed rollers by means of a U-shaped bridge 17, forming part of the frame 16, and disposed above the wire. The wire moves along in the grooves of the guide rollers 18, 18, carried by the frame 16, being held in said 95 grooves by the pressure roller 19 which presses against the upper side of the wire. The pressure roller is vertically adjustable 100 so as to accommodate wires of different sizes. It is necessary that the wire be wound under tension and the pressure roller 19 imparts the tension required.

Mounted on the frame 16 there is a die roller 20, and above it, the punching roller 105 21. These respective rollers are clamped on and rotate with the spindles 22 and 23, which in turn rotate on the sleeves 24 and 25, mounted, respectively, on the bearing rods 26 and 27. The spindles have the internal 110 annular oil chambers 28 and 29, which surround the sleeves 24 and 25, and from which

lead the ports 30 and 31. Oil is admitted into the oil chambers through the respective ducts 32 and 33, for lubricating the sleeve bearings. This mechanism is suitably mounted in a frame consisting of the side members 34 and 35, which in turn is secured to the frame 16. The die roller 22 has an annular groove 36 of the same cross sectional contour as that of the screen wire, and at its top this groove is widened on one side forming an abrupt annular shoulder 37 which is set back from the main groove the exact distance the turns of the screen wire are to be spaced apart. The punching roller 23 carries a plurality of projecting radiating punches 38 whose points are aligned with the groove 36 so as to strike the wire between its longitudinal center and its edge toward the shoulder 37. This alignment is maintained by the annular rib 39 of one spindle which runs in an annular groove 40 of the other spindle.

As before stated the wire is pulled through between the rollers by the rotation of the pipe 4, and the punches indent the top side of the wire and thereby throw out the spacer lugs 41, on one side. The height of these lugs is determined by the annular shoulder 37 against which they abut as thrown out. This shoulder not only insures the uniformity in height of the lugs, but also forms their crests with flat faces 42 which form seats for the lugs against the adjacent turns of the wire in winding, as illustrated in Figure 6.

As the wire winds on the pipe 4, the lugs of the turn being wound are forced up closely against the preceding turn of wire by means of a pressure roller 43 which is rotatably mounted on the lower end of the spindle 44. This spindle depends from the anchor 45, which in turn is secured to the frame 16. This frame 16 is mounted to pivot on the vertical axis by means of the bearing 45', which is mounted on the vertical spindle 46 carried by the lathe carriage 2. The frame 16 is also mounted to pivot on a horizontal axis by means of the horizontal bearing 47 which is formed integrally with the bearing 45' by the web 48. A spindle 49 is fastened to the frame 16 and has a bearing in said horizontal bearing 47. The outer end of the spindle 49 has a forwardly extending rod 50, pivoted thereto which works through a bearing 51 carried by the carriage 2. The outer end of this rod has a head 52 and interposed between the head 52 and the bearing 51, and surrounding the rod 50 there is a coil pressure spring 53. This spring operates to hold the pressure roller 43 yieldingly against the wire as wound on the pipe.

The spacer lugs hold the turns of wire suitably spaced apart on the pipe, thus providing a screening surface.

The end of the frame 16, opposite its pivotal support on its horizontal bearing 47, has an open bearing 54, and an adjusting rod 55 is anchored to the lathe carriage and stands up through said bearing 54 and its upper end is provided with a head 56. There is a slideable collar 57 which rests on the frame 16 and through which the rod 55 slides and a coil spring 58 surrounds said rod and is interposed between the head 56 and the collar 57. This coil spring operates to hold the pressure roller yieldingly against the pipe.

It is to be noted that the carriage heretofore designated by the numeral 2 has a movable section 2', capable of adjustment relative to the rest of the carriage. This section 2' of the carriage carries the split bearing 6 through which the screw shaft 5 is threaded.

The main body of the carriage 2 has aligned bearings 59, 59 through which the stays 60, 60 slide. These stays are attached to the section 2'. There is a rotary internally threaded sleeve 61, which has a swiveling connection with the main carriage 2 and this sleeve 61 is turnable through the hand grips 62 carried thereby. There is an outwardly threaded rod 63 fastened at one end to the carriage section 2', and it is threaded through the sleeve 61. Inasmuch as the frame 16 is carried by the main body of the carriage 2, this frame and the winding mechanism carried thereby, may be adjusted relative to the work by the adjustment of the carriage sections, relative to each other, through the mechanism hereinbefore described, provided for that purpose.

It is to be further noted that the punching roller is adjustable relative to the die roller, so that the stroke of the punches against the wire can be easily controlled. This adjustment can be accomplished by turning the bearing rod 27 which is eccentric relative to the punching roller. This rod may be readily turned through the collar 64 which is splined on said rod, as shown in Figure 4. This adjustment is also necessary to facilitate the threading of the wire through between these rollers in beginning the work or winding.

It is also to be noted that there is a shim 65 between the die roller 20 and the opposing shoulder of the spindle 22 on which it is mounted. By varying the thickness of this shim, or the number of shims, the roller 20 can be laterally adjusted and the point of contact of the punches 38 relative to the edge of the wire, thus regulated.

What I claim is:

1. In a wire winding machine, a die roller having a peripheral groove, a punching roller spaced from the die roller, projecting punches radiating from the punching roller, and aligned with said groove, spindles on

which said rollers are mounted, said spindles having internal annular oil chambers provided with inlet ducts, bearing sleeves on which the spindles are mounted, said sleeves having oil ports, bearing rods on which the sleeves are mounted, and a frame in which said rods are mounted.

2. In a wire winding machine, a die roller having a peripheral groove, a punching roller spaced from the die roller, projecting punches radiating from the punching roller and aligned with said groove, spindles on which said rollers are mounted, bearing rods on which said spindles are mounted, a frame supporting said rods, one of said spindles having an annular groove and an annular rib carried by the other spindle and running in said annular groove.

3. In a wire winding machine, mechanism including a die roller having a peripheral groove, a punching roller spaced from the die roller, projecting punches radiating from the punching roller and aligned with said groove, means permitting the adjustment of one of said rollers on its bearing to vary the position of said punches laterally with respect to said groove, means for adjusting one of said rollers toward and from the other roller, a carriage formed of two sections, for driving the same, said mechanism being mounted on the other section, and means for adjusting said sections toward and from each other.

In testimony whereof I have signed my name to this specification.

EMIL H. MEYER.
